COUNTER MOLDING MECHANISM

Milton L. Dodge, Newburyport, Mass.

Application October 12, 1931, Serial No. 568,308

22 Claims. (Cl. 12—66)

This invention relates to the molding of counter stiffeners for shoes and more particularly to those made from fiberboard or the like.

The mechanism of this invention is intended more especially to form the stiffener with a downwardly extending marginal bead about the outer edge of the stiffener attaching flange. In one embodiment of this invention, this bead is formed hollow on its upper face from a stiffener previously molded to form a flat flange, which flat flange itself, may, if desired, be molded by the same mechanism in a cycle of operations preliminary to that in which the hollow bead is formed.

In another embodiment of this invention a stiffener previously molded to produce the hollow bead is further treated to make the bead of solid cross section.

For a more complete understanding of this invention, reference may be had to the accompanying drawings in which

Figure 1 is a perspective of a last or plug and a flange plate for use in molding the stiffener with a flat flange and thereafter to form a hollow bead in the flange.

Figure 2 is a central vertical section through the same showing a stiffener blank in position therein for the first molding operation.

Figure 3 is a similar section but showing the positions of cooperating molding parts while molding a flat flange.

Figures 4 and 5 are fragmentary sections similar to portions of Figures 2 and 3, respectively, but showing parts positioned for forming a hollow bead about the outer margin of the flange.

Figures 6 to 9 are perspectives showing successive stages in the molding of the blank, Figure 9 showing in section the flange bead formed solid in cross section.

Figure 10 is a somewhat diagrammatic side elevation of a counter molding machine of a well known type provided with molding mechanism for solidifying the bead.

Figure 11 is a front elevation to a larger scale of the molding portion of the machine of Figure 10.

Figure 12 is a section on line 12—12 of Figure 11, but showing the counter in position.

Figures 13, 14 and 15 are sections similar to Figure 12 or portions thereof, but showing the parts in successive positions during a molding cycle.

Referring first to the construction shown in Figures 1 to 5, at 1 is shown a plug or last block having an end portion 2 of the general shape of

the heel end of a last except that the sole simulating face is provided about its margin with an outwardly extending bead 3. At 4 is shown a plate member shaped to engage the sole face 5 of the last member throughout substantially its entire heel end portion inwardly of the bead which passes around the sides and rear end of the plate member 4. As shown this plate member is carried at the upper end of a standard 6 which passes within a slot 7 in the sole face of 10 the last member, and is shown as hinged as by the pintle pin 8 between spaced portions 9 at the lower end of the member 4. When the plate member 4 is brought up toward the last face 5 the standard 6 throughout substantially its entire length passes into the slot 7 and is housed thereby. At the lower end of the standard 6 is shown a handle 10 by which the plate member 4 may be moved toward or from a position adjacent to the last sole face 5.

The last block 1 is designed to have placed over its end portion 2 a counter blank such as 12 shown in position thereon in Figure 2 and by itself in Figure 6. This blank is curved to the general contour of the top and sides of the last member and is so held during the molding operation by any suitable means such as the well known side molds, a portion of which means is shown at 13 in Figure 3, the counter being placed between these parts with its lower margin extending therebeyond as shown at 14 in Figure 2. The plate member 4 being swung outwardly into the position shown in Figures 2 and 3, a flange wiper 15, which in general may be of well known construction, is passed across the protruding portion 14 of the counter blank so as to wipe this portion inwardly over the bead 3, as shown in Figure 3, to form an in-turned attaching flange for the counter in the usual manner. By this means the counter may be molded to the proper curvature and may be provided with an inturned substantially flat attaching flange 14 as shown in Figure 7.

If desired, of course, the substantially flat in-turned flange might be formed by any other well known mechanism. By whatever means it may be formed initially flat, the mechanism herein shown may be operated so as to produce an outwardly extending hollow marginal bead about the outer margin of the flange. The operations to do this are shown in Figures 4 and 5. The wiper 15 being retracted, the plate 4 is moved toward the last member so that it engages the inturned flange of the counter inwardly of the last bead 3 in the position shown in Figure 4. The wiper 55

15 is then passed across the outer face of the plate 4 and in order that it may do so easily, it is shown as provided with a roller 16 at its forward end which engages the upper end of the 5 plate 4, and as the wiper descends crowds the plate 4 inwardly toward the last face 5 so as to conform the counter flange to the contour of the bead 3 on the last member and to the sole face 5 of the last member inwardly thereof and 10 adjacent thereto. On retraction of the wiper 15 and removal of the counter it has the general appearance shown in Figure 8.

The counter is then ready for the final molding 15 operation, which consists in compacting the flange material so as to form the outwardly extending marginal bead of substantially solid cross section. The mechanism for accomplishing this is shown in Figures 10 to 15. Referring first to Figure 10, at 20 is illustrated a machine standard 15 or frame of a well known type of counter molding machine. This frame 20 has pivoted at 21 thereto a lever 22 which has pivoted at 23 thereto a table member 24. The table member is 20 also pivotally connected to the frame by a link 25 pivoted at one end 26 thereto and at its other at 21 to the frame 20, so that as the lever 22 is swung about its fulcrum 21 the table 24 is moved up and down in substantially a straight line. A cam 30 carried by a shaft 31 operates 25 through a heavy spring 32 against the lower end portion of the lever 22 so as to rock this lever at suitable times. The shaft 31 also has a crank arm 35 to which is connected a pitman 36 extending to one end of a lever 37 fulcrumed at 30 38 at the top of the machine. The forward end of this lever 37 is connected by a link 39 to a vertically reciprocable wiper carrier 40. This wiper carrier may carry the wiper 15 shown in Figures 3 and 5, which wiper may also be used 35 in connection with the final molding operation as will later be described. The shaft 31 is rotated in any suitable manner as through the intermeshing gears 41 and 42, the gear 42 being carried by a main actuating shaft 43 driven in any 40 suitable manner. The table 24 has resting thereon a plate 50 (see Figures 12 and 13) from which is supported by the spring 51 a last member 52. This last member may have its upper end formed 45 similarly to the last member 1 of Figures 1 to 5, except that it is unprovided with the marginal bead 3 at its sole face, but instead is flat to its extreme edge. It is provided with a slot 54 similar to the slot 7 and there is also provided a plate 55 similar to the plate 4 and carried by 50 a standard 56. The standard 56, however, instead of being directly pivoted to the last member 52 as in the constructions hereinbefore described is pivoted to the plate 50 as at 57 so that it may have a vertical movement relative 55 to the last member 52 when the spring 51 is compressed. One or more pins 60 may extend upwardly from the plate 50 and engage in suitable sockets 61 in the last member 52 so as to insure a substantially straight up and down relative motion between the last member and the plate 50. The standard 56 passes rearwardly of a cross bar 65 secured at opposite ends to the last member 52 and this cross bar acts on a cam face 67 on the outer face of the standard. 60 A spring 68 secured to the last member 52 bears against the inner face of the standard 56 and presses this standard out against the cross bar 65 as far as is permitted by the cam face 67.

When the last member 52 is elevated with respect to the plate 50, the plate 55 is held outward- 65

ly from the sole face of the last member 52, as is shown in Figure 12, and in this position of the parts the counter with its hollow marginal bead 70 may be placed over the upper end of the member 52. Above the member 52 the machine carries the usual side molds 71, shown best in Figure 11, which may be of the usual type, which close together against the counter on upward pressure of the last member with the counter thereon thereagainst. As this is a common construction, 10 no detailed description is believed necessary. The counter being in position over the last member 52,—the table 24 preferably having a hinged top to permit the last member and the plate 55 to be swung forwardly as a unit, as shown in 15 dotted lines in Figure 10 to facilitate the placing or removal of the counter,—the last member is raised by the raising of the table 24 until the counter is engaged by the side clamping members 20 71 which press the counter sides against the sides of the last member 52, stopping further upward motion of the last member 52, whereupon the spring 51 is compressed as the plate member 50 carrying the standard 56 therewith continues to 25 rise.

The action of the cam face 67 on the cross bar 65 then causes the plate member 55 to move upwardly and inwardly into contact with the inner portion of the counter flange, as shown in Figure 30 13, and as this motion is continued, it engages the flange material and forces it upwardly, compressing it between the upper edge of the plate member 55 and the outer conforming means 71, as shown in Figure 14. The wiper 15 is then brought 35 down over the outer face of the plate 55, engaging the bead material extending outwardly beyond the edge of the conforming means 71 and the outer face of the plate 55, and compresses this material between these members, as shown in 40 Figure 15, so as to condense the bead into substantially solid cross section, as is shown in Figure 9 at 75. Further operation of the machine causes the wiper 15 to retract and the last member 52 and the plate 55 to descend and separate 45 from each other, whereupon the completely molded stiffener may be removed.

From the foregoing description of certain embodiments of this invention, it should be evident to those skilled in the art that various changes 50 and modifications might be made without departing from the spirit or scope of this invention as defined by the appended claims.

I claim:

1. Counter molding mechanism including a last member over which the counter to be molded may be placed, a plate member engageable with the inner marginal portion of the counter flange turned over the sole face of said last member, and a wiper movable across the outer portion of said counter flange and the outer face of said plate member.
2. Counter molding mechanism including a last member over which the counter to be molded may be placed, a plate member engageable with the inner marginal portion of the counter flange turned over the sole face of said last member, and a wiper movable across the outer portion of said counter flange and the outer face of said plate member, said last member having a marginal bead extending from its sole face and about the edge of said plate member when said plate member is positioned to press said flange against said last member.

3. Counter molding mechanism including a last member over which the counter to be molded may be placed, and a plate member having a hinge connection to said last member and movable from and to a position engaging the inner marginal portion of the counter flange inturned over the sole face of said last member and provided with a flat face for engagement with the outer face of said counter flange.
4. Counter molding mechanism including a last member over which the counter to be molded may be placed, and a plate member having a hinge connection to said last member and movable from and to a position engaging the inner marginal portion of the counter flange inturned over the sole face of said last member, said last member having a marginal bead extending outwardly from its sole face about the edge of said plate when said plate is in said position.
5. Counter molding mechanism including a last member over which the counter to be molded may be placed, a plate member having a hinge connection to said last member and movable from and to a position engaging the inner marginal portion of the counter flange inturned over the sole face of said last member, and a wiper movable across the outer portion of said counter flange and the outer face of said plate member and pressing said plate member against said flange.
6. Counter molding mechanism including a last member over which the counter to be molded may be placed, and a plate member having a hinge connection to said last member and movable from and to a position engaging the inner marginal portion of the counter flange inturned over the sole face of said last member, said last member having a marginal bead extending outwardly from its sole face about the edge of said plate when said plate is in said position, and a wiper movable across the outer portion of said counter flange and the outer face of said plate member and pressing said plate member against said flange inwardly of said body portion.
7. Counter molding mechanism including a last member over which a counter to be molded may be placed, a plate member engageable with the inner marginal portion of the counter flange inturned over the sole face of said last member, said last member having a marginal outwardly extending bead about the margin of said plate member when said plate member is in engagement with said flange, and a member movable across the sole face of said last member outwardly of said plate in position to press said plate toward said last member sole face to cause said flange to be conformed to the contours of said bead and said sole face inwardly of said bead.
8. Counter molding mechanism including a last member over which the counter to be molded may be placed, said last member having an outwardly extended marginal bead on its sole face, a plate member movable to and from a position engaging the counter flange inturned over said sole face and inwardly of said bead, and a flange wiper movable across said last member sole face for inturning said flange when said plate member is out of said position, and for engaging the outer face of said plate member when it is in said position and forcing it toward said sole face to cause said flange to be conformed to the contours of said bead and said sole face inwardly of said bead and adjacent thereto.
9. Counter molding mechanism including a last member over which a counter having an out-
- wardly extended hollow marginal bead in its attaching flange may be placed, a plate engageable with the outer face of said flange inwardly of said bead, means for conforming the stiffener to the sides and heel end of said last member, means for moving said plate toward said conforming means to crowd the material of said flange bead together at the heel end of said counter, and a wiper movable across the edge of said conforming means and the outer face of said plate for compacting the flange material between said plate last member and conforming means into a bead of substantially solid cross section.
10. Counter molding mechanism comprising a frame, a platform movable up and down on said frame, a last member over which a counter having a marginal hollow bead in its attaching flange may be placed spring supported above said platform, means carried by said frame above said last member for conforming said contour to said last member on the upward movement of said last member, a plate member shaped to engage said counter flange inwardly of said bead and connected to move with said platform, and cam connections between said plate and last members for pressing said plate member firmly against said flange on upward movement of said plate member relatively to said last member on compression of said spring support to engage the inner face of said bead and to compress said bead into substantially solid cross section.
11. Counter molding mechanism comprising a frame, a platform movable up and down on said frame, a last member over which a counter having a marginal hollow bead in its attaching flange may be placed spring supported above said platform, means carried by said frame above said last member for conforming said counter to said last member on the upward movement of said last member, a plate member shaped to engage said counter flange inwardly of said bead and connected to move with said platform, cam connections between said plate and last members for pressing said plate member firmly against said flange on upward movement of said plate member relatively to said last member on compression of said spring support to engage the inner face of said bead and to compress said bead into substantially solid cross section, and a wiper movable across the outer face of said plate and engaging and compacting said bead between said last and plate members and said forming means.
12. Counter molding mechanism including a last member on which a counter having a hollow marginal bead in its attaching flange may be placed, a supporting plate for said last member, spring means for yieldingly holding said supporting plate spaced from said last member, a standard pivoted to said supporting plate, a flange engaging plate carried by the upper end of said standard in position to engage said counter flange inwardly of said bead when said last member and supporting plate are in said spaced relation, a cross bar with which said standard may engage for limiting the movement of said flange engaging plate away from said last member, a spring pressing said standard against said cross bar, and a cam face on said standard acting on said cross bar to press said flange engaging plate against the flange of said counter on relative approach between said last member and said supporting plate.
13. Counter molding mechanism including a last member over which a counter to be molded may be placed, means for wiping a sole attaching

flange on said counter so placed, and a member carried by and cooperating with said last member for forming an outwardly extending marginal bead on said flange.

5 14. Counter molding mechanism including a last member over which a counter to be molded may be placed, means for wiping a sole attaching flange on said counter so placed, and a member carried by and cooperating with said last member 10 and wiping means for forming an outwardly extending marginal bead on said flange.

15 15. Counter molding mechanism including a last member, a plate member attached to said last member, and means for pressing said plate member toward the sole face of said last member to engage between them the flange of a counter carried by said last member.

20 16. Counter molding mechanism including a last member over which the counter to be molded may be placed, a member engageable with the outer face of said counter, and a plate member engageable with the inner marginal portion of the counter flange inturned over the sole face of said last member and having an edge portion 25 inwardly of said second mentioned member and movable relatively to said first-mentioned members to form up a bead portion of substantially solid cross section from material of said flange outwardly of said edge portion.

25 17. Counter molding mechanism including a last member over which the counter to be molded may be placed, and a member carried by said last member for engagement with the inner marginal portion of a counter flange inturned over the sole face of said last member and provided with a flat face for engagement with the outer face 30 of said counter flange.

30 18. Counter molding mechanism including a last member over which the counter to be molded

may be placed, and a member connected to said last member for pivotal movement from and to engagement with the outer face of a counter flange inturned over the sole face of said last member and throughout substantially its entire 5 heel end portion.

19. Counter molding mechanism including a last member over which the counter to be molded may be placed, and a member connected to said last member for pivotal movement from and to 10 engagement with a counter flange inturned over the sole face of said last member and for movement parallel to said face.

20. Counter molding mechanism including a last member over which the counter to be molded 15 may be placed, a member connected to said last member for pivotal movement from and to engagement with the outer face of a counter flange inturned over the sole face of said last member and throughout substantially its entire heel end 20 portion, and means for pressing said flange-engaging member toward said last member.

21. Counter molding mechanism including a last member over which the counter to be molded may be placed, a plate engageable with the inner 25 marginal portion of the counter flange in-turned over the sole face of said last member, and a roller movable across the outer face of said plate member.

22. Counter molding mechanism including a 30 last member over which the counter to be molded may be placed, a plate engageable with the inner marginal portion of the counter flange in-turned over the sole face of said last member, a wiper movable across the outer portion of said counter 35 flange and the outer face of said plate member, and a roller carried by said wiper engaging said plate member.

MILTON L. DODGE.
